DELPHIA, PENNSYLVANIA, A CORPORATION OF NEW JERSEY.

INSULATOR-PIN.

1,094,852.

Specification of Letters Patent. Patented Apr. 28, 1914.

Application filed August 4, 1911. Serial No. 642,273.

To all whom it may concern:

Be it known that we, JULIUS L. HECHT, a resident of Evanston, in the county of Cook and State of Illinois, and JOTHAM C. GAPEN, a resident of Oak Park, in the county of Cook and State of Illinois, citizens of the United States, have invented new and useful Improvements in Insulator-Pins, of which the following is a full, clear, concise, and exact 10 description, reference being had to the accompanying drawing, forming a part of this specification.

Our invention relates to improvements in insulator pins of that class in which is provided a strain taking base, held in position by a bolt passing through the cross arm, which bolt is adapted to receive the insulator.

One of the objects of our invention is to 20 provide a pin of this type which may be secured upon the cross arm of the conductor carrying pole prior to the erection of the pole, in position to receive the insulator after the pole has been erected.

It is a further object of our invention to 25 provide an insulator pin of this type of such construction that the insulator may be rotated to any position even though the base portion is fixed, so that the conductor receiving groove in the insulator will be in alinement with the conductor.

For the purpose of disclosing our invention we have illustrated one embodiment thereof in the accompanying drawings.

In said drawings Figure 1 is a transverse sectional view of an insulator pin constructed according to our invention and shows the supporting pin attached to a cross arm; Fig. 2 is a perspective view showing the pin 35 mounted on a cross arm.

In the construction illustrated we provide a base member 1 which preferably consists of a hollow tubular portion provided with tapering angularly disposed strengthening 45 ribs 2. The hollow base portion terminates in a rectangular bottom 3 which is somewhat curved or inclined in transverse section as shown in Fig. 1. This curvature not only acts as a water shed to shed the rain or 50 moisture, but also permits the bottom to fit over the curved or rounded top on the cross arm 4 and places the strain on the outer edges of the cross arm. The rectangular bottom is provided with a pair of down-

wardly extending lips 5 which fit over the 55 sides of the cross arm to prevent the base member from rotating. This base member 1 is secured in position on the cross arm by a bolt 5' which extends clear through it and through the cross arm and is threaded at its 60 lower end as at 6 to receive the securing nut 7. The upper end of the bolt 5' is provided with a collar 8 arranged during the erection of the pole to engage an internal annular flange 9 formed in a recess 10 in the base 65 member. We have shown the collar 8 as being integrally formed with the bolt 5, but it will be understood that any form of collar may be used if desired, as for instance, a nut may be secured upon the threaded portion 11 70 of the bolt. The bolt 5', at its upper end, is threaded as at 11 to receive the threaded thimble 12 of the insulator 13.

We have shown in the drawing the collar 8 in the position which it finally assumes 75 after the insulator has been secured upon the pin. In this position it will be noted there is a slight clearance between the collar 8 and the annular flange 9. This clearance is particularly provided so that the thimble 12 80 of the insulator will engage the upper surface of the support 1 in order to insure as much of the lateral strain as is possible being taken by the support and to relieve as much as possible the bolt 5' from any lateral 85 strain. In securing the base 1 to the cross arm prior to the erection of the pole, however, it is customary to have the collar engage the annular flange 9 in the base member 90 to hold the base member in position until after the pole has been erected and the insulator secured in position. This collar also serves the additional purpose of preventing the bolt from dropping out of the base and cross arm when a damaged insulator is removed prior to the installing of a new insulator.

In the erection of electrical transmission lines it is desirable that as much of the equipment as possible be assembled prior to 100 the erection of the poles. It is therefore desirable that the insulator pins be secured in position prior to the erection of the poles. It is also desirable that some means be provided after the erection of the pole whereby 105 the insulators which are to be used may be readily secured to the pin and then alined so that the conductor receiving groove will

- be in proper alignment with the conductor. The collar 8 serves to lock the base member 1 to the cross arm prior to the erection of the pole and at the same time does not interfere 5 with the rotation of the insulator to properly align the groove thereof with the conductor and does not interfere with the proper engagement between the thimble 12 and the top surface of the base.
- 10 While we have shown and described one embodiment of our invention it will be understood that various modifications and changes may be made therein without departing from the spirit of our invention as 15 set forth in the accompanying claims.
- Having thus described our invention, what we claim as new and desire to secure by Letters Patent is:
1. The combination with an insulator support comprising a hollow base mounted upon a cross-arm, a bolt for securing said base in position on the cross-arm screw-threaded at both ends, one end projecting beneath the cross-arm to receive a nut and the other 20 end projecting above the base, of an insulator comprising a conductor-carrying member and an internally screw-threaded thimble screwing on said projecting end of the bolt engaging the top of the base and clamping 25 the base onto the cross-arm, and laterally projecting means on the bolt below the top of the base and independent of the insulator for preventing the bolt from dropping through the arm when the base and bolt alone are assembled on the cross-arm, said means permitting a free vertical movement of the 30 bolt with respect to the base to allow the groove in the top of the insulator to be properly aligned and at the same time have the thimble of the insulator seat on and clamp the base in position.
  2. The combination with an insulator support comprising a hollow base mounted upon a cross-arm, a bolt for securing said base in position on the cross-arm screw-threaded at both ends, one end projecting beneath the cross-arm to receive a nut and the other end 35 projecting above the base, of an insulator comprising a conductor-carrying member and an internally screw-threaded thimble screwing on the projecting end of the bolt engaging on the top of the base and clamping the base onto the cross-arm, and a collar on said bolt arranged to engage a shoulder formed in said base below the top thereof to prevent the bolt from dropping through the base 40 and arm after the bolt and base have been assembled on the cross-arm, said collar permitting a free vertical movement of the bolt with respect to the base to allow the insulator to be properly adjusted on the base 45 and at the same time have its thimble seat on and clamp the base in position.

In witness whereof, we have hereunto subscribed our names in the presence of two witnesses.

3. The combination with an insulator support comprising a hollow base mounted upon a cross-arm, a bolt for securing said base in position on the cross-arm screw-threaded at both ends, one end projecting beneath the cross-arm to receive a nut and the other end projecting above the base, of an insulator comprising a conductor-carrying member and an internally screw-threaded thimble screwing on the projecting end of the bolt engaging on the top of the base and clamping the base onto the cross-arm, and a collar on said bolt arranged to engage a shoulder formed in said base below the top thereof to prevent the bolt from dropping through the base 40 and arm after the bolt and base have been assembled on the cross-arm, said collar permitting a free vertical movement of the bolt with respect to the base to allow the insulator to be properly adjusted on the base 45 and at the same time have its thimble seat on and clamp the base in position.

In witness whereof, we have hereunto subscribed our names in the presence of two witnesses.
